J. Neems,

Tobacco Press.

Patented Dec. 15, 1835.

John W. Weems

Letters Patent.

The schedule referred to in these Letters Patent, and making part of the same, containing a description in the words of the said John W. Weems himself, of his improvement in the press for passing Tobacco and other substances.

Be it known, that I, John W. Weems, of West River, Anne Arundel County, State of Maryland, have made an improvement in the useful arts; being a machine for passing Tobacco and other substances, called "Weems' Tobacco Press," which is described as follows, reference being had to the annexed drawings of the same making part of this specification. This press consists of a strong frame, A, resting upon the ground, composed of two sills, B, of suitable size and strength, placed parallel to each other, and connected together by suitable cross pieces, C. At or near one end of the frame is erected the head block, D, against which the hogshead rests in which the tobacco is placed, and made very strong by proper braces, & framing; and in the rear of this head block is a windlass, E, to assist in the operation of pressing. At or the centre of the frame are erected two stout uprights, F, mortised, tenoned and braced into the sills, to receive & support the gear. A cogged driver, G, having a small piston, G, on one end for passing the tobacco into the hogshead, works longitudinally between these uprights. At the other end of the driver, is a gear, H, to which are attached chains leading to the windlass, for assisting in the operation of pressing. The gear consists of a small pinion, I, fixed on a shaft, turning in suitable boxes in the uprights, which pinion works in the cog of the driver, & propels it horizontally. On this shaft is a large cog wheel, K, into which works another small pinion, L, fixed on a shaft, M, turning in boxes in the uprights, & whose ends project beyond each side of the uprights sufficiently far

to admit one or two driving or tread wheels to be fastened thereon for propelling the piston. Operation. The driver being run back, the hoghead into which the tobacco is to be pressed, is laid longitudinally upon the frame, with its bottom against the head block. Then a long race, or one or more other hogheads, are placed in front of the one into which the whole is to be pressed. The tobacco to be pressed, being previously hard packed into these several hogheads; - the large tread wheel is then turned which turns the small pinion on its shaft; this turns the large cogwheel, upon whose shaft is fixed the other small pinion; this works in the cog of the driver, and propels it with the piston against the tobacco, & presses it into the last hoghead; the driver is then run back - the filled hoghead removed, & another hoghead put in its place, and the operation continued as before.

What follows is my invention, & which I desire to secure by Letters Patent, consists in the before described press for pressing tobacco, and other substances.

and his copr.
